(57) **CLAIM**

The ornamental design for a waterproof camera, as shown
and described.

DESCRIPTION

FIG. 1 is a perspective view of a waterproof camera showing
my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plain view thereof; and,

FIG. 8 is a perspective view showing the application thereof,
wherein the broken line portion is for illustrative purpose
only and forms no part of the claimed design.
